UNITED STATES PATENT OFFICE.

DAVID GESTETNER, OF LONDON, ENGLAND.

DUPLICATING, MANIFOLDING, AND THE LIKE.

1,354,478.

Specification of Letters Patent.

Patented Oct. 5, 1920.

No Drawing.

Application filed February 26, 1919. Serial No. 279,422.

To all whom it may concern:

Be it known that I, DAVID GESTETNER, a subject of the King of Great Britain and Ireland, and residing at Neo-Cyclostyle 5 Works, Tottenham Hale, London, N. 17, England, have invented certain new and useful Improvements in and Relating to Duplicating, Manifolding, and the like, of which the following is a specification.

10 This invention relates to methods of duplicating or manifolding, and has for its object to provide a method of duplicating or manifolding which shall produce copies resembling prints produced by the employment of an engraved plate, that is to say, prints in which the ink stands up on the impression receiving surface.

According to the invention a stencil, produced upon a Yoshino or like paper or on a 20 suitable textile fabric, such as bolting cloth, by the employment of a photographic process of the kind in which the action of light is made use of for changing the solubility of a composition in regard to a solvent 25 liquid used as a developer, is secured on a surface between which and the stencil an appreciably thick layer of a suitable ink is interposed, and prints or copies are produced by bringing the impression receiving 30 surface into contact with the stencil surface.

In forming the stencil, a process relying upon the capacity of gelatin or gum to be rendered insoluble as the result of the action of light upon certain sensitizing bodies may 35 be employed.

Of processes of this kind, what are known as the gum bichromate and carbon processes may be specified.

In producing a stencil according to the 40 carbon process, the print may be first made upon a light sensitive gelatin surface which may then be transferred to a temporary support and after development may be transferred from the temporary support to the 45 Yoshino or like paper or suitable fabric.

Alternatively, the sensitized colloid surface may be applied in the first instance to the Yoshino or like paper or suitable fabric, which, after exposure under a suitable positive or negative to the action of light, is developed in order to effect the removal of the soluble colloid and produce a stencil; for instance, the Yoshino paper may, according to this method of operation, be impregnated 50 with a sensitized gelatin solution and the paper thus treated may be subjected to the

action of light under a positive or negative for the purpose of producing the stencil.

Alternatively, the Yoshino or like paper or other fabric may be sensitized by means 60 of suitable sensitizing solutions, for instance, a mixture of a bichromate and manganous sulfate, which will yield a photographic print capable of, when brought into contact with a colloid surface, for instance, 65 a layer of gelatin such as what is known as carbon tissue, rendering the carbon tissue insoluble at those places where light has caused a chemical change in the sensitizing body.

In accordance with the invention the capacity of asphaltum which, as is well known, can be rendered insoluble in benzin or similar compounds by the action of light, 70 may be made use of for producing stencils 75 resistant to the action of certain inks, for instance, water inks containing relatively considerable proportions of gum to give to them a suitable consistency of brilliant appearance when dry.

According to this phase of the invention, the Yoshino or like paper or other suitable fabric may, if desired, be coated or impregnated with the asphaltum, or a print may be produced on a sheet of paper coated with 80 asphaltum and the print then transferred to a sheet of Yoshino or like paper or other suitable fabric.

The stencil produced in the above or in any other suitable manner if necessary or 90 desirable after treatment with a softening agent such as glycerin is secured to a suitable supporting surface which has been provided with a coating of a suitable ink. The inks employed have, preferably, a composition 95 similar to those of the inks at present used in processes of reproduction involving the employment of engraved plates, that is to say, they are varnish inks or inks containing a suitable proportion of a water soluble gum or the like, and with advantage they have the character of the inks used in embossing in that they do not soak into the impression receiving surface to any considerable extent.

It is further to be noted that the layer of ink on the support should be of appreciable thickness in order that the impression receiving surface shall take up a sufficient quantity of ink to produce the desired effect.

Impressions are taken from the stencil an

impression receiving surface with the aid, if necessary, of sufficient pressure to produce the desired contact.

As will be understood, the detailed description of producing a stencil by photographic means is furnished solely for the purpose of describing the nature of the invention and not for the purpose of limitation.

10 In conclusion it may be mentioned that the method of printing or producing copies employed in accordance with the invention is only practicable when stencils produced in the manner specified are used as stencils 15 produced on porous supports by mechanical means as, for instance, by the employment of a typewriter or style, do not have sufficiently fine lines or such clearly defined boundaries to the thicker lines to produce 20 prints or copies possessing a satisfactory appearance.

Having now described my invention, what I claim as new and desire to secure by Letters Patent is: —

25 1. A method of duplicating or manifold-

ing in which a stencil, produced upon a Yoshino or like paper or on a suitable textile fabric, such as bolting cloth, by the employment of a photographic process of the kind in which the action of light is made 30 use of for changing the solubility of a composition in regard to a solvent liquid used as a developer, is secured on a surface between which and the stencil an appreciably thick layer of a suitable ink is interposed, 35 and prints or copies are produced by bringing the impression receiving surface into contact with the stencil surface.

2. The process of duplicating, in which a stencil produced on a porous support by 40 photographic means is secured to a suitable supporting surface which has been provided with an appreciably thick layer of an ink having a composition similar to those of the inks at present used in processes of reproduction involving the employment of engraved plates.

In testimony whereof I have signed my name to this specification.

DAVID GESTETNER.
